ABSTRACT OF THE DISCLOSURE

A baseball base assembly having a baseball base constructed of a unitary covering sheath and filled with spongeous composition material. An anchoring bracket is mounted on the underside of the base by means of bolts and cooperating wood plugs set in the spongeous material. A mounting sleeve extends outwardly from the anchoring bracket and is adapted to telescopingly engage and key with an anchoring post embedded in the ground.

BACKGROUND OF THE INVENTION

The present invention relates generally to baseball bases and more particularly to a baseball base assembly with an improved anchoring device.

In the past, conventional cloth-covered baseball bases were anchored in place on the ground by means of straps on the base which were fastened to stakes which were driven into the ground. Such strap and stake-anchoring arrangements for bases are not entirely satisfactory, however, in that the straps are prone to becoming loose or twisted under the strains and impacts of ordinary use. Aside from the inconvenience of playing a baseball game with a loosened base, such a base poses a danger to the players in that they can easily catch the spikes of their shoes on the loosened straps, or catch their feet under the base itself, causing falls which can and do result in serious injuries.

Because cloth-covered bases cannot be left exposed to the elements, they are customarily taken in after each use and fixing in place or removing the baseball base by means of straps, as well as maintaining the straps in a properly tightened condition, is a time-consuming task. Therefore, various devices were employed to eliminate the relatively continual manipulation of the straps. One method of accomplishing this is to permanently strap the base onto an anchoring plate and provide a stake permanently embedded in the ground which cooperates with the anchoring plate to securely hold the base in position. An example of such a device is that disclosed in Patent No. 2,695,784 issued Nov. 30, 1954, to Louis A. Orsatti et al.

Further developments in the construction of baseball bases have resulted in the elimination of cloth coverings by providing unitary plastic sheaths which are impervious to the elements and which are filled with a relatively low cost, spongeous, plastic composition material. While such bases last significantly longer than conventional cloth-covered bases, and could be left exposed to the elements, they are still customarily taken in after use, among other reasons, to permit refinishing of the infield area. The need for a convenient base-anchoring device is therefore still present. However, even such modern plastic-sheath baseball bases could not heretofore be attached to the anchoring devices mentioned above without the use of conventional straps. Therefore, prevention of the physical danger to the players and maintenance of the base firmly in its proper place on the anchor plate still required that continual attention be given to the proper adjustment of the straps.

SUMMARY OF THE INVENTION

To solve the above problems in quickly and conveniently anchoring a baseball base in place on the ground

2

and to eliminate the straps normally used with such bases, the present invention provides a new and improved anchoring device for baseball bases and particularly for bases having unitary plastic sheaths filled with a spongeous composition material.

- 5 In the illustrated preferred embodiment, an anchoring bracket is attached to the underside of the base by means of bolts which are threaded into wooden plugs set in the spongeous filler of the base, thus eliminating the need for straps. The wooden plugs are of relatively large diameter compared to that of the bolts to provide sufficient surface contact with the spongeous material to firmly hold the plugs in place. The wooden plugs also provide a rigid material to which the bolts may be secured.
- 10 The anchoring bracket and attached base cooperate with an anchoring post permanently embedded in the ground to firmly fix the base in position flush with the ground surface.
- 15 As an aid in firmly securing the base, and the plastic sheath itself, to the anchoring bracket, integral tubular projections are provided on the portions of the sheath through which the bolts pass. The projections fit into holes provided in the wooden plugs and the bolts pass through the projections and into the plugs.
- 20 As an added reinforcement of the sheath and to seal the base, a thin plastic sealing sheet is sealed in place over the underside of the base between the sheath and anchoring bracket.
- 25

BRIEF DESCRIPTION OF THE DRAWING

FIGURE 1 is a perspective view of a baseball base anchored in place on the ground by means of the anchoring device of the invention, with portions of the base, anchoring device and ground being shown in section;

35 FIGURE 2 is a sectional view of a baseball base anchored in place by means of the present anchoring device;

FIGURE 3 is an enlarged fragmentary view in the direction of lines 3—3 of FIGURE 1;

40 FIGURE 4 is an exploded perspective view of portions of the anchoring device shown on a reduced scale; and

FIGURE 5 is an enlarged fragmentary sectional view of a portion of a baseball base and attached anchoring device.

45 DESCRIPTION OF THE PREFERRED EMBODIMENT

Referring to the drawing, the preferred embodiment of the baseball base anchoring device is adapted for use with a baseball base 10 which generally has a unitary sheath 12 made of a plastic material which encases a block of spongeous filler material 14 which has the shape of a conventional baseball base. An anchor bracket 16 is mounted on the underside of the base 10 by means of four bolts 18. The bolts 18 are securely fastened to wooden plugs 20 which are set in holes 22 in the spongeous filler 14.

The anchor bracket 16 has a sleeve section 24 extending outwardly from the center of the bracket. The internal area of the sleeve section 24 has a rectangular cross-section and the base 10 is anchored in place by telescoping the sleeve section 24 over an anchor post 26, also with a rectangular cross-section, which is upstanding in a recess 28 in the ground.

65 The anchor post 26 is securely anchored in the recess 28 by a lower mounting section 30 on the post which is embedded in a concrete block 32 buried in the ground. The anchor post 26 and concrete block 32 are set in the ground so that the top 34 of the anchor post does not extend above ground level.

70 With the sleeve section 24 of the anchor bracket 16 telescoped on the anchor post 26, it can be seen that the

base cannot be moved horizontally along the ground and the rectangular cross-section of the keyed post and sleeve section prevent rotational movement of the base.

More particularly, the plastic sheath 12 is a single molded unit which completely encases the top and sides of the filler material 14. To increase the strength of the base construction and to aid its secure attachment to the anchoring device, the sheath 12 also extends a sufficient distance over the underside of the base so that the edges of the sheath are held between a flat plate portion 36 of the anchor bracket 16 and the wooden plugs 20 when bolts 18 are tightened. To add further strength to the sheath 12 at the points where the bolts 18 pass through it, tubular projections 38 integral with the sheath extend into countersunk holes 40 in the wooden plugs 20. To reinforce the sheath 12 and to aid in water-proofing the base 10, a thin sealing sheet 42 of plastic material is heat-sealed in place over the underside of the sheath, as shown in FIGURE 3.

As was briefly mentioned above, the anchor plate is attached to the underside of the base 10 by means of the four bolts 18, rather than the conventional straps. However, the spongeous filler material 14 is too soft and elastic to withstand the shear and compressive forces which would be developed if the bolts 18 were threaded directly into the filler material. These bolting forces are therefore distributed over a relatively large area of the filler 14 by means of the wooden plugs 20. The wooden plugs 20 are conveniently constructed with a circular cross-section having a diameter substantially greater than the diameter of the bolts 18. It is to be noted, however, that the wooden plugs 20 could be constructed in any shape which provides contact with the filler 14 over a relatively large area. The wooden plugs 20 are mounted in appropriate holes 22 in the filler material 14 and are secured by means of any suitably adhesive. The bottom of the plugs 20 are disposed flush with the bottom of the filler material 14 but the plugs do not extend completely through this filler in order to provide spongeous padding on the top portions of the base 10. In effect, the wooden plugs 20 provide areas of sufficient rigidity to withstand the compressive forces developed by the bolts 18 in a spongeous material which could not otherwise withstand such forces.

While bolts designed for use with wood could be employed to attach the anchor plate 16 to the underside of the base 10, it has been found to be preferable for ease in bolting to employ bolts 18 which have threads ordinarily used with pre-formed metal threads. The bolts 18 extend into bores 43 through the wooden plugs 20. Suitable internal metal threads for the bolts 18 are provided by threaded inserts 44 extending into the bores 43 at the ends of the plugs opposite those in which the bolts 18 are inserted. The shear forces developed on the threads by tightening the bolts 18 are therefore applied to metal rather than a relatively soft wood of the plugs 20. The compressive forces developed by tightening the bolts are applied to the wooden plugs 20 by circular flanges 45 on the inserts 44 which extend over the ends of the plugs.

The base 10 is mounted on the anchor bracket 16 by inserting the bolts 18 through the bracket, the thin sealing sheet 42, tubular projections 38 on the sheath 12 and into the bores 43 in the plugs 20. Threading of the bolts into the inserts 44 draws the underside of the base 10 and intermediate sheath 12 and sheet 42 tight against the plate portion 36 of the anchor bracket 16. The tightening force is transferred through the bolts 18 and inserts 44 to the wooden plugs 20 and thence to the filler 14 through the surface areas of the plugs. The sheath 12 and reinforcing sealing sheet 42 are clamped between the plugs 20 and plate portion 36 further securing the base 10 in place on the anchor bracket 16.

In the embodiment illustrated, the anchor bracket 16 has a generally square, flat plate portion 36 with four bolt holes 46 near the corners of the plate for mounting the base 10 onto the bracket. The sleeve section 24 of the

anchor bracket 16 extends outwardly from the plane of the plate portion 36 at its center. As noted above, the internal area of the sleeve section 24 is rectangular in cross-section and is adapted to telescope and key with the anchor post 26.

The base 10 and attached bracket 16 are held in place on the ground by the anchor post 26 which is substantially fixed against movement with respect to the ground. It will be appreciated that there are numerous ways of fixing the anchor post 26 in the ground and that the illustrated method is only the presently preferred way. The illustrated anchor post 26 has a lower mounting section 30 which is embedded in the concrete or cement-filled center portion of a concrete or cement block 32. As an aid to securing the anchor post 26 in the concrete, two pair of transverse reinforcing lugs 48 project outwardly from the mounting section 30 with each pair of lugs at a right angle to the other.

The anchor post 26 and concrete block 32 are embedded in the ground at the appropriate place on the playing field with the anchor post 26 set in a substantially vertical attitude. In order for the underside of the base 10 to rest flush with the ground, the top 34 of the anchor post is at, or preferably slightly below, ground level. To provide clearance between the ground and the sleeve section 24 of the anchor bracket 16, a recess 28 is left around the upstanding portion of the anchor post 26.

The anchor post 26 and concrete block 32 are horizontally angularly oriented in the ground so that when the sleeve section 24 of the anchor bracket 16 is telescoped and keyed onto the anchor post 26, the anchored base 10 will also have the proper horizontal angular orientation with respect to the playing field.

The baseball base anchoring device of the present invention then provides a means for quickly and simply anchoring a baseball base in proper position flush with a playing field and which requires little or no maintenance as there are no straps to be cared for or adjusted.

It will be understood that, while particular forms of the invention have been illustrated and described, modifications of design and construction can be made without departing from the spirit and scope of the invention. Hence, the invention is not to be limited except as defined in the appended claims.

I claim:

1. In combination, a baseball base having a cover portion filled with a spongeous composition material, and an anchoring device for use with said base comprising:

post means adapted to be securely anchored in the ground;

bracket means adapted to detachably engage said post means, said bracket means having a plate portion disposed on the underside of said baseball base; and plug means attached to said plate portion and extending into said composition material, said plug means having a bottom surface engaging said cover portion and securely clamping said cover portion between said plate portion and said bottom surface.

2. The combination of claim 1, wherein:

said post means has a substantially rectangular cross-section; and
said bracket means includes a sleeve section with an internal area having a substantially rectangular cross-section adapted to telescope and key with said post means.

3. The combination of claim 1, wherein said plug means is adhesively mounted in holes in the spongeous composition material filling the baseball base.

4. The combination of claim 1, wherein said plug means comprises a plurality of plug members mounted in spaced holes in the spongeous composition material filling the baseball base.

5. The combination of claim 1, wherein said plug means comprises four plug members mounted in spaced

holes in the spongeous composition material filling the baseball base.

6. A baseball base assembly, comprising:
 a baseball base having a unitary molded sheath encasing the top, sides and portions of the bottom of a spongeous composition filler;
 post means adapted to be embedded in the ground in a substantially vertical attitude, said post means having a substantially rectangular cross-section;
 bracket means having a plate portion and a sleeve section, said sleeve section having an integral area of substantially rectangular cross-section and adapted to detachably telescope and key with said post means;
 a plurality of plug means adhesively mounted in holes in the spongeous composition filler of said baseball base; and
 bolt means associated, one each, with said plug means for attaching said bracket means to said baseball base, each of said bolt means extending through said portion of said sheath disposed over the bottom of the baseball base and into its respective plug means, the cross-sectional area of said plug means being substantially greater than that of said bolt means.

15

20

7. The baseball base assembly of claim 6, including tubular projections integral with the portion of said sheath disposed over the bottom of said baseball base, said projection being disposed around its respective bolt means and extending into holes in said plug means.

5 8. The baseball base assembly of claim 6, including a sealing sheet disposed on the underside of said baseball base between said plate portion of said bracket means and the portion of said sheath disposed over the bottom of said baseball base, said sealing sheet being sealingly joined around its entire perimeter to said sheath.

10 9. The baseball base assembly of claim 6, including threaded inserts mounted in said plug means for cooperating with said bolt means to attach said bracket means to said baseball base.
